CLAIM

The ornamental design for an explosion-proof light, as shown and described.

DESCRIPTION

FIG. 1 is a perspective view of an explosion-proof light showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view showing the explosion-proof light installed on a ceiling; and,

FIG. 9 is another perspective view showing the explosion-proof light installed on a light holder.

The broken lines in the drawings illustrate portions of the explosion-proof light that forms no part of the claimed design.
